UNITED STATES PATENT OFFICE.

JAMES J. ROSS, OF DETROIT, MICHIGAN, ASSIGNOR TO THE THREE RIVERS RAILWAY SUPPLY COMPANY, OF THREE RIVERS, MICHIGAN.

ALARM-SIGNAL.

SPECIFICATION forming part of Letters Patent No. 666,067, dated January 15, 1901.

Application filed March 26, 1900. Serial No. 10,174. (No model.)

To all whom it may concern:

Be it known that I, JAMES J. ROSS, a citizen of the United States, residing at Detroit, in the county of Wayne and State of Michigan, 5 have invented certain new and useful Improvements in Alarm-Signals, of which the following is a specification, reference being had therein to the accompanying drawings.

The invention relates to certain improvements upon the electric signal apparatus shown and described in Letters Patent No. 522,431, which issued to me July 3, 1894; and it consists in the novel arrangement of the circuits, whereby but one battery and a less 15 number of contact-points are required to produce the desired results.

In the drawings, Figure 1 is a diagrammatic view showing the general arrangement of the circuits and the electrical appliances, the 20 alarm-circuit and its two branches being shown in full and broken lines, respectively. Fig. 2 is a diagrammatic view of the main circuit, and Figs. 3 and 4 are similar views of the auxiliary circuit.

25 In the drawings thus briefly referred to the reference-letters A A' designate two track-sections upon opposite sides of a crossing, which are properly insulated in the usual manner.

30 B B' are the track-batteries for the blocks described, and C C' are the track-relays, provided, respectively, with armatures C² and C³.

D represents the single battery common to all the circuits.

35 E is the locking-relay, and F represents the alarm-bell, which is located at the crossing.

The letter G designates the alarm-circuit, which includes the battery D, alarm-bell F, of any ordinary type, a normally-closed break 40 K, controlled by a switch in the form of an armature L of the circuit-closing relay E, and two branches H and I between the points a and b. The branch H (shown in full lines, Fig. 1) includes a normally open break J, controlled by the armature of the track-relay C'.

45 The branch I (illustrated in dotted lines in the same figure) includes the break M, normally open, which is controlled by the armature of the relay C.

50 The letter P represents the main circuit

(shown in full lines, Fig. 2) and includes the battery D, circuit-closing relay E, and the normally open breaks S and S'.

P' designates an auxiliary circuit which includes between the points a and b the branches 55 H and I, before described in connection with the alarm-circuit, the battery and relay E, just referred to, and the normally open break T.

The several circuits and their arrangement having been thus described, the operation of 60 the mechanism is as follows: Upon the entrance of a train in the block A' the track-battery B' therefor is short-circuited, the track-relay C' cut out, and its armature permitted to drop, thereby closing the normally open breaks J and S. The break K being 65 normally closed, the short-circuiting of the track-battery B' establishes the alarm-circuit through its branch H, as plainly indicated in Fig. 1, and the bell is caused to ring. 70

Upon the entrance of the train into the block A from the block A' the track-battery B is short-circuited and the track-relay C cut out. The armature of said latter relay drops and closes the normally open breaks S' and M. The 75 break S having been closed upon the short-circuiting of the battery B', the closing of the break S' establishes the main circuit through the relay E and the two normally open breaks S and S', as plainly indicated in the full lines, 80 Fig. 2. Upon the passage of the train entirely out of the block A' into the block A the relay C' is again energized by its track-battery, the breaks J and S opened, and the auxiliary circuit P' is established through its 85 branch I, as indicated by the full lines in Fig. 4. This latter circuit is maintained until the train passes entirely out of the block A, when the relay E is deenergized, the break K closed, the track-relay C energized by its 90 battery, and the breaks S' and M opened. The parts of the mechanism are thus restored to their initial position in readiness to signal the next train.

It will be obvious from the description of 95 the mechanism that if a train should enter the insulated track-sections by way of the block A the operation just described would be practically repeated, with the exception that the auxiliary circuit would be estab- 100

lished through the branch H, as indicated in Fig. 3, and the alarm-circuit through the branch I.

What I claim as my invention is—

In an electric signal for railway-crossings, the combination of an alarm-circuit having two branches each containing a normally open break, track-relays corresponding in number to and controlling the breaks in the alarm-circuit branches, a circuit-closing relay, a main circuit including said circuit-closing relay and two normally open breaks controlled

by the track-relays, and an auxiliary circuit including the circuit-closing relay, a normally open break controlled by said latter 15 relay, and having two branches each including a normally open break controlled by one of the track-relays.

In testimony whereof I affix my signature in presence of two witnesses.

JAMES J. ROSS.
